CELLO STEM RESTRAINER

Sheldon M. Rosen, 151-31 88th St.,
Howard Beach, N.Y. 11414

Filed Nov. 1, 1971, Ser. No. 194,782

Term of patent 14 years

Int. Cl. D17—99

U.S. Cl. D56—1 R

FIG. 2

FIG. 3

FIG. 4

FIG. 5

FIG. 6

FIG. 1 is a perspective view of a cello stem restrainer, showing my new design;

FIG. 2 is a top plan view;

FIG. 3 is a side elevational view, the opposite side being substantially a mirror image thereof;

FIG. 4 is a bottom plan view;

FIG. 5 is an end elevational view;

FIG. 6 is an opposite end elevational view, and

FIG. 7 is a cross-sectional view thereof taken on line 7—7 in FIG. 1.

I claim:

The ornamental design for a cello stem restrainer, as shown and described.
